UNITED STATES PATENT OFFICE

GUSTAVE M. FAUSER, OF ARDSLEY-ON-HUDSON, NEW YORK, ASSIGNOR TO CONGOLEUM-NAIRN INC., A CORPORATION OF NEW YORK

DESIGN FOR LINOLEUM OR SIMILAR HARD-SURFACED FLOOR COVERING

Application filed December 12, 1929. Serial No. 33,770. Term of patent 7 years.

To all whom it may concern:

Be it known that I, GUSTAVE M. FAUSER, a citizen of the United States of America, residing at Ardsley-on-Hudson, in the county of Westchester and State of New York, have invented a certain new, original, and ornamental Design for Linoleum or Similar Hard-Surfaced Floor Covering, of which the following is a specification, reference being had to the accompanying drawing forming a part hereof.

The figure is a plan view of a piece of linoleum or similar hard-surfaced floor covering, showing my new design.

The drawing shows in full the floral element appearing in one of the four corners of the present design. The floral decorations in the four corners constitute respective quarters of the complete floral element shown in the lower right corner of the drawing.

I claim:

The ornamental design for linoleum or similar hard-surfaced floor covering substantially as shown and described.

In testimony whereof I affix my signature.

GUSTAVE M. FAUSER.
